Primary Examiner — Leanne Was-Englehart*(74) Attorney, Agent, or Firm* — Birch, Stewart, Kolasch & Birch, LLP(57) **CLAIM**

The ornamental design for a lamp with sound, as shown and described.

DESCRIPTION

FIG. 1 is a front, right perspective view of the lamp with sound showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken lines depict portions of the lamp with sound that form no part of the claimed design.

1 Claim, 7 Drawing Sheets(56)
